ASH TRAY

Lewis W. Harms, Denver, and Lillian Harms,
Loveland, Colo.

Application March 14, 1952, Serial No. 18,986

Term of patent 14 years

(Cl. D85—2)

To all whom it may concern:

We, Lewis W. Harms and Lillian Harms, citizens of the United States, residing respectively at the city and county of Denver and State of Colorado, and at Loveland, county of Larimer, State of Colorado, have invented a new, original, and ornamental Design for an Ash Tray, of which the following is a specification, reference being had to the accompanying drawing, forming part hereof.

Fig. 1 is a top plan view of an ash tray, showing our new design;

Fig. 2 is a side elevation thereof;

Fig. 3 is a section taken on line 3—3, Fig. 1; and

Fig. 4 is a section taken on line 4—4 Fig. 1. The side not shown has the same appearance as the side shown in Fig. 2.

We claim:

The ornamental design for an ash tray, as shown and described.

LEWIS W. HARMS.
